UNITED STATES PATENT OFFICE.

EARL SHERWOOD, OF HONESDALE, PENNSYLVANIA.

CAR-FENDER.

No. 858,225.

Specification of Letters Patent.

Patented June 25, 1907.

Application filed March 15, 1907. Serial No. 362,438.

To all whom it may concern:

Be it known that I, EARL SHERWOOD, a citizen of the United States, residing at Honesdale, in the county of Wayne and 5 State of Pennsylvania, have invented a certain new and useful Car-Fender, of which the following is a specification, reference being had therein to the accompanying drawings.

This invention relates to car fenders and 10 the main object of the invention is to provide simple and reliable means for quickly depressing the forward end of the scoop to adapt the fender to successfully pick up objects of any kind and size lying on the road 15 bed.

A further object of the invention is to construct and mount the fender tripping mechanism, that the scoop may be supported directly thereon and rendered detachable, enabling the said scoop to be quickly placed in 20 position on the car and as quickly removed therefrom when desired for any purpose whatever.

Another object of the invention is to provide a novel construction of buffer for the 25 front end of the scoop which will insure the picking up of all objects large or small without injury either to the objects or the buffer or fender which buffer is detachably mounted on and connected with the scoop, enabling the same to be quickly taken off and repaired should it become necessary.

A further object of the invention is to provide a wheel guard and an operating gate 35 therefor with operative connections arranged and adapted to permit the gate to swing entirely out of the way after the wheel guard has been tripped to receive and pick up an object.

With the above and other objects in view, 40 the nature of which will more fully appear as the description proceeds, the invention consists in the novel construction, combination and arrangement of parts, herein fully described, illustrated and claimed.

In the accompanying drawings:—Figure 1 is a side elevation of one end of a car, showing the fender of this invention applied thereto. Fig. 2 is a horizontal section taken on the 50 line 2—2 of Fig. 1. Fig. 3 is a detail vertical section taken in line with the foot depressed plunger pin. Fig. 4 is an enlarged detail section through the front of the fender. Fig. 5 is a side elevation of the fender, showing the 55 scoop folded up against the dash board, illus-

trating a modification in the tripping mechanism.

The front section or scoop of the fender comprises the oppositely arranged side bars 1, connected at the front by the forward cross bars 2, braces (not shown) connecting the side bars with the front cross bar, and the side bars being provided with heel extensions or arms 3, by means of which the scoop is supported on the trip hereinafter particularly described. Extending upward from the side bars 1 are short standards 4 to which is pivotally connected the back frame 5 of the fender scoop, said back frame embodying the side bars 6 and a connecting bar 7 extending across the top of the back frame and adapted to engage over retainer hooks 8 on the car, whereby said back frame is securely held in position, as shown in Fig. 1.

In carrying out the present invention I 75 employ a trip embodying a pair of oppositely arranged arms or short levers 9, connected by a cross bar 10 for simultaneous operation. The arms or levers 9 are fulcrumed at points intermediate their ends, as 80 at 11 on hangers 12 which are rigidly connected to the car body as indicated in Fig. 1, and said arms or levers are provided at their forward ends with laterally projecting pivot pins or studs 13 which enter and pass 85 through corresponding holes in the rear ends of the heel ends of the side bars of the scoop at the front of the car and as clearly shown in Fig. 1 and also in Fig. 2. It will thus be seen that the front scoop is connected directly with and supported upon the trip above described and that said scoop may be 90 quickly attached to and disconnected from the trip by simply deflecting the heel ends of the arms or extensions 3 of the scoop until 95 the pins 13 pass into or out of engagement with the holes in said extensions.

To operate the trip above described, under the preferred embodiment of this invention I 100 employ a plunger pin 14 which normally projects slightly above the car platform as shown in Figs. 1 and 3. This pin is movable up and down within a guide tube 15 fastened to the car. Slidably mounted in the lower portion of said tube is a plunger 16 having at 105 its lower end a fork 17 which straddles a short lever arm 18 fast on the cross bar 10 of the trip above described. A spring 19 connects the cross bar 10 with the car and acts to restore the trip to its normal position after 110

the same has been operated by the plunger pin.

From the foregoing description, it will be seen that by depressing the plunger pin 14, 5 the trip is rocked on the fulcrum points 11, causing it to elevate the rear ends of the arms 3 and depress the forward end of the scoop into contact with the road bed so as to insure the picking up of any object in the way. 10 When the pin 14 is released, the spring 19 acts to restore the trip to its normal position and thereby again elevate and sustain the forward edge of the scoop in the position in 15 which it is ordinarily carried, free from the road bed.

Detachably connected with the front cross bar 2 of the scoop is a buffer, which, as best illustrated in Fig. 4, comprises an upper clamping strip 20 and a lower clamping strip 21, between which is clamped and held a resilient or elastic strip 22. This strip 22 projects considerably in advance of the clamping strips and the front of the scoop and is the first thing which comes in contact with the 25 road bed and the objects to be picked up by the fender. Owing to its elasticity or flexibility and the particular arrangement thereof, the forward edge of the strip 22 is adapted to readily yield either upward or downward, 30 being disposed substantially in a horizontal position, thereby preventing the object from getting under the scoop and by rolling over, said strip 22 forms an excellent cushion which absorbs the impact and prevents injury both to the object picked up and the 35 fender itself. The upper clamping strip 20 also comprises an inclined portion or skid 23 which extends from the top surface of the strip 22 upward and backward to the front 40 cross bar 2 of the scoop and acts to deflect the objects picked up and direct them onto the scoop. To provide for detaching the buffer from the scoop, I employ a plurality of clips or holders, each L-shaped as shown in 45 Fig. 4, or in other words comprising an arm 24 which extends under the cross bar 2 and buffer, and a vertical arm 25 which extends up behind the cross bar 2. The arm 24 is secured to the buffer by passing a bolt or 50 other suitable fastener through such arm and the clamping strips and resilient strip, while a readily detachable fastener 26, such as a screw, connects the clip or holder to the cross bar 2. By removing the several screws or 55 fasteners 26, the buffer as a whole may be removed from the scoop, repaired and replaced.

The wheel guard 27 embodies a frame somewhat resembling the scoop above described, and the side bars 28 thereof are provided with upstanding short stanchions 29 which are pivotally attached to hangers 30 rigidly connected to the car, as indicated in Fig. 1. In rear of the pivotal mounting of 65 the wheel guard, the heel ends or rearward

extensions 31 of the side bars 28 are connected with the car by means of oppositely arranged sets of toggle levers or links 32, while from the pivotal points at the inner adjacent ends of the toggle levers, connecting 70 rods 33 extend forward and have a jointed connection with a swinging gate 34 fulcrumed at its upper edge as shown at 35, on the car. This gate comprises the two side bars 36 and one or two or more cross bars 37, 75 and if desired a tubular casing 38 may be placed around the lower cross bar, being left free to act as a roller to permit an object to pass the more easily beneath and lift the gate just in advance of the wheel guard. 80

The forward ends of the connecting rods 33 are enlarged and provided with upwardly extending slots 39 in which pins or studs 40 on the side bars 36 work to allow the gate to swing up entirely out of the way as a large 85 object passes beneath the same and is picked up by the wheel guard. The gate extends low enough to be acted upon by a child, and yet, by providing the slots 39, a full grown person may also pass under the gate to be 90 picked up by the wheel guard, the said gate swinging up amply far to permit this. It will also be seen that the gate acts with a positive movement to trip the wheel guard and depress the front end thereof, which, like 95 the front scoop, is provided with a buffer 41 of corresponding construction.

Instead of the trip operating mechanism above described, other operating mechanism may be employed, such as is shown in Fig. 5, 100 wherein the trip is shown as deflected or bent upward behind the hangers 12, while the cross bar of the trip has connected thereto a link 42 which extends back and connects with a hand lever 43 fulcrumed on the car as 105 shown and arranged within convenient reach of the motorman, who by rocking said lever may rock the trip and depress the forward edge of the scoop. Should the motorman not have time to trip the scoop, the forward edge of said scoop will be depressed automatically by the object with which it 110 comes in contact, and should the object be small enough to pass under the forward scoop, it will be caught and picked up by the 115 wheel guard in the manner above described.

I claim:

1. A car fender embodying a scoop, and means for supporting and tilting the scoop comprising a trip carried by the car and having the scoop pivotally supported thereon, and manually operated means for operating said trip. 120

2. A car fender comprising hangers for rigid attachment to a car, a trip fulcrumed on said hangers, means for operating said trip, and a scoop having a detachable pivotal connection with said trip. 125

3. A car fender comprising hangers for rigid attachment to a car, a trip fulcrumed 130

on said hangers, a manually operated plunger for operating said trip, and a scoop having a detachable pivotal connection with said trip.

5. A car fender comprising hangers for rigid attachment to a car, a trip fulcrumed on said hangers, a scoop having a detachable pivotal connection with said trip, a manually operated device for operating said trip, 10 and a spring for restoring the trip and scoop to their normal positions.

15. A car fender comprising a tilting wheel guard fulcrumed intermediate its front and rear end, toggle levers connecting said guard in rear of its fulcrum with a fixed part of the car, a swinging guard-operating gate, and one or more operating rods connecting the toggle levers and gate, whereby the gate actuates the wheel guard with a positive movement.

20. A car fender comprising a tilting wheel

guard, toggle-levers connecting said guard with the car, a swinging guard-operating gate, and one or more rods connecting the toggle-levers and gate and having their ends 25 slotted to permit the gate to swing out of the way after tripping the wheel guard.

7. A car fender comprising a scoop embodying a front cross bar, and a buffer secured to said cross bar and embodying superimposed clamping strips one of which is provided with an inclined upper portion, a resilient strip held between the clamping strips and projecting in advance thereof, and means for detachably securing said buffer to 30 the front cross bar of the scoop.

In testimony whereof I affix my signature in presence of two witnesses.

EARL SHERWOOD.
